US00D627006S

(12) **United States Design Patent**
Katz

(10) **Patent No.:** **US D627,006 S**
(45) **Date of Patent:** **** Nov. 9, 2010**

(54) **GAME TABLE**

(76) Inventor: **Marcus A. Katz**, 7752 Fisher Island Dr.,
Miami Beach, FL (US) 33109-0943

(**) Term: **14 Years**

(21) Appl. No.: **29/339,635**

(22) Filed: **Jul. 2, 2009**

Related U.S. Application Data

(63) Continuation-in-part of application No. 12/348,150, filed on Feb. 2, 2009, which is a continuation-in-part of application No. 12/090,851, filed as application No. PCT/US2007/72792 on Jul. 3, 2007.

(51) **LOC (9) Cl.** **21-03**

(52) **U.S. Cl.** **D21/369; D21/397**

(58) **Field of Classification Search** **D6/511; D21/369, 385, 396-397; 273/274, 292; 463/13, 463/17, 20, 25, 46-47**

(57) **CLAIM**

The ornamental design for a game table, substantially as shown and described.

DESCRIPTION

FIG. 1 is a cross-sectional view of the game table showing my new design, taken along line 1—1 in FIG. 5;

FIG. 2 is a cross-sectional view thereof, take along line 2—2 in FIG. 5;

FIG. 3 is a top plan view thereof;

FIG. 4 is a top plan view of a second embodiment thereof;

FIG. 5 is a top plan view of a third embodiment;

FIG. 6 is a top plan view of a fourth embodiment;

FIG. 7 is a top plan view of a fifth embodiment;

FIG. 8 is a top plan view of a sixth embodiment;

FIG. 9 is a top plan view of a seventh embodiment;

FIG. 10 is a top plan view of an eighth embodiment;

FIG. 11 is a top plan view of a ninth embodiment;

FIG. 12 is a top plan view of a tenth embodiment;

FIG. 13 is a top plan view of an eleventh embodiment;

FIG. 14 is a top plan view of a twelfth embodiment;

FIG. 15 is a cross-sectional view thereof, taken along line 15—15 in FIGS. 6 and 12;

FIG. 16 is a cross-sectional view thereof, taken along line 16—16 in FIGS. 6 and 12;

FIG. 17 is a cross-sectional view thereof, taken along line 17—17 in FIG. 9; and,

FIG. 18 is a cross-sectional view thereof, taken along line 18—18 in FIG. 9.
